DEASHING OF RESIDUAL FRACTIONS

Charles Newton Kimberlin, Jr., and Clark Edward Adams, Baton Rouge, La., and Wilfred O. Taff, Westfield, N.J., assignors to Esso Research and Engineering Company, a corporation of Delaware

Application June 13, 1958, Serial No. 741,353

7 Claims. (Cl. 208—86)

The present invention relates to the removal of metallic contaminants from petroleum oils and more particularly relates to an improved process for the removal of complex organo-metallic compounds of the porphyrin type, in particular nickel and vanadium, from high boiling petroleum gas oils and residua.

It has long been recognized that petroleum gas oils and residua which include constituents boiling in excess of about 950° F. normally contain iron, nickel, vanadium and other metallic contaminants which have an adverse effect upon various catalysts employed in petroleum processing operations and upon combustion equipment in which such petroleum fractions are burned as fuels. In operations such as catalytic cracking, hydrofining and the like, the presence of very small concentrations of these contaminants in the feed stream leads to the rapid poisoning of the catalyst, causing a significant decrease in the product yield, an increase in coke and gas production, and a marked shortening in the life of the catalyst. In residual type fuels, such contaminants attack the refractories used to line boilers and combustion chambers; cause slagging and the build-up of deposits upon boiler tubes, combustion chamber walls and the blades of gas turbines; and severely corrode high temperature metallic surfaces with which they come into contact.

Although there have been numerous methods proposed in the past for removing these contaminants from high boiling petroleum fractions, it has been found that such methods are largely ineffective, generally result in the loss of substantial quantities of the oil, and in most cases are prohibitively expensive. As a result, it has generally been necessary to restrict the feed streams to catalytic petroleum processing units to those fractions which boil below the range in which the contaminants are found and to avoid as much as possible the use in fuels of fractions which contain the contaminants in high concentrations.

The present invention provides a new and improved process for the removal of iron, nickel, vanadium, and other metallic contaminants of the porphyrin type from high boiling petroleum oils, and in particular residual oils. In accordance with the present invention, such contaminants are removed by subjecting the contaminated oil sequentially to a thermal treatment, treating the heat soaked material with 1 to 10 volumes of a light hydrocarbon preferably in the presence of an acidic gas. In a preferred embodiment of the invention the solvent-residual oil mixture is also subjected to a sludging treatment with an immiscible sludging component having a high affinity for aromatics, preferably anhydrous liquid SO_2 .

The concentration of metallic contaminants and the ratio of volatile to non-volatile contaminants in crude oils vary considerably. The metals content of any distillate fraction will therefore depend upon the type and concentration of contaminants in the crude oil from which the fraction was distilled, the boiling range of the fraction, and the amount of entrainment which took place during the distillation. Heavy gas oil distilled from typical crudes may contain from about 1 to about 20 pounds

2

of metallic contaminants per 1000 barrels. Residual fractions and gas oils derived from crudes which are particularly high in contaminants may contain as much as 300 pounds of metal per 1000 barrels. Similarly, in some fractions these contaminants may be predominantly of the volatile type and in others they may be essentially of the non-volatile type, depending upon the crude source and the conditions under which the fraction was obtained.

The heat soaking step of the present invention is carried out preferably under conditions of incipient cracking so that no significant amount of lighter components are formed. The conditions required will depend upon a combination of time and temperature, the nature of the feed stock, and the like. The temperature of thermal treatment, however, is below 1000° F. and preferably below about 900° F. On the other hand, temperatures above about 600° F. are needed for sufficient reaction rate to maintain times within reasonable limits. Pressures may also be applied to the thermal treating step to maintain the material in a substantially liquid phase.

The solvent precipitation step which follows is carried out in the heat soaked feed stock directly. Preferred are light hydrocarbons boiling in the range of about 55° to 400° F. As a result of the solvent addition, there is precipitated as a light, flocculent precipitate the so-called asphaltenes fraction, which is extremely difficult to remove from the solution phase. A portion of the porphyrins are precipitated with these asphaltenes, while a portion remains in solution.

Accordingly, there is also employed as a metal coagulating reagent an acidic material soluble in the petroleum fractions, a hydrogen halide such as anhydrous HCl , or BF_3 , preferably dry hydrogen chloride. The treating temperature, the volume of hydrogen halide employed and the pressure at which the treatment is carried out may be varied considerably. It is preferred to treat the solvent-residual oil mixture at temperatures between about 70° and 400° F., although higher temperatures may be employed, and at pressures ranging from atmospheric to about 300 p.s.i.g., higher pressures being also permissible. The reaction time too may be varied from a few minutes to as much as a few hours, depending upon the treating conditions.

Though this combination gives good results in demetallizing residual oils, even better results can be obtained by addition of a sludging component, and in particular liquid anhydrous sulfur dioxide. A sludging action occurs which serves to coagulate the flocculent asphaltene precipitate, enabling its ready separation as a sticky semi-fluid sludge. The final product obtained by this combination processing is found to be extremely low in metal content, thus enabling the residual oil to be used for turbines and the like.

The exact nature and process of the present invention, its objects and advantages, will be more fully understood from the following description and drawing showing schematically a preferred embodiment of the invention.

Turning now to the drawing, reference numeral 1 designates a crude oil distillation zone which may constitute, for example, an atmospheric pipe still or a combination of atmospheric and vacuum distillation towers. Crude oil may be introduced into distillation zone 1 through line 2 and separated into a variety of fractions of different boiling ranges. Light hydrocarbons in the C_1 to C_4 range may be taken off through overhead line 3. A naphtha fraction may be drawn off through line 4 and in one embodiment of the present invention, this naphtha stream, boiling in the range of 55° to 300° F. and comprising hydrocarbons having from 5 to 10 carbon atoms, provides the solvent employed in the demetallizing step.

Middle distillates may be withdrawn through line 5. These materials, kerosene and light gas oils, may boil up to 900° F. and are substantially metal free. A heavy gas oil fraction boiling in the range of between 950° F. and 1300° F. is withdrawn through line 6 and the residual fraction, boiling above the heavy gas oil is taken off as bottoms product through line 7. Both of these latter streams contain substantial amounts of metallic constituents and may be subjected separately to the treating process of the present invention.

The thermal treating zone 8 to which the metal contaminated heavy oil is passed via line 7, is preferably a closed, agitated vessel or drum. The pressure during the heat soaking step is preferably maintained between 200 to 1500 p.s.i.g. As indicated previously, it is advantageous to maintain a temperature of from about 650° to 850° F. in this zone under conditions such that little if any cracking occurs. A residence period of 0.1 to 5 hours is desirable. The effect of the thermal treatment serves to increase markedly the susceptibility of the metallic constituents to later coagulation by the acidic gas treatment, possibly by changing either the character of the porphyrin, the asphaltenes, or the oil.

The solvent precipitation step is carried out on the heat-soaked residua directly, and the latter is passed for this purpose through line 9 to contacting tower 10. This may comprise one or more towers or other vessels adapted to permit the saturation of the oil with gaseous HCl admitted through line 15 under the desired conditions of temperature and pressure. Suitable coils, jacketing, or other temperature control means are provided, as are means for agitation.

Solvent, which is preferably an aliphatic or naphthenic hydrocarbon or mixture having 5 to 10 carbon atoms, and which may advantageously be the naphtha fraction withdrawn through line 4 from still 1, is introduced into vessel 10 through line 12, in amounts of from 0.1 to 10 volumes per volume of oil, preferably 0.3 to 3 volumes per volume of oil. Furthermore, in a preferred embodiment of the invention, 0.1 to 3 volumes of liquid sulfur dioxide per volume of oil are admitted through line 17 to effect sludging of the coagulated metallic components.

Reaction conditions within tower 10, which is preferably maintained as a countercurrent reaction zone, are temperatures of 30° to 300° F. and pressures of 25 to 500 p.s.i.g. The residence time of the oil may range from 5 to 100 minutes or more. The deashed oil-solvent mixture, along with gaseous HCl or other acidic metal coagulating gas is passed overhead via line 14 and passed through heater 16 to flash tower 18, where the hydrocarbon solvent along with HCl and any dissolved SO₂ is flashed off overhead through line 20, while oil of exceptionally low metal content is recovered from flash zone 18 through line 19. The flashed solvent and gases are passed to cooler 24 via lines 20 and 22, and thence to settler 26, which is maintained under conditions of decreased temperature and increased pressure to liquefy the SO₂.

Returning now to tower 10, the semi-fluid sludge is withdrawn downwardly through line 34 and is, in a preferred embodiment of the present invention, further processed to recover the sulfur dioxide. This may be done by passing it through heating zone 36 into a fluidized solids flash zone 38. Here a bed of finely divided solids, preferably derived from previously treated asphaltene, is maintained as a dense, fluidized bed of solids maintained by an upward flowing gas stream admitted through line 41. This bed of solids may be at a temperature of about 100° to 1000° F., and the sludge is deposited thereon, whereby it is decomposed to a solid carbonaceous material and gaseous SO₂ and hydrocarbon. These gases are withdrawn through cyclone 40 equipped with dipleg 42 for return of fines to the fluidized bed, and are passed via lines 43 and 22 to settler 26. A portion is recycled via line 41 to reactor 38 to maintain the bed in fluidized

condition. Solid carbonaceous residue may be withdrawn through line 45 and be used as solid fuel.

In the settling zone, which is adapted to settle out and separate liquid SO₂ from solvent hydrocarbon, HCl may be withdrawn overhead as uncondensed gas via line 28 for recycle to the system or may be recycled dissolved in liquid streams. Similarly, the hydrocarbon solvent forms an upper layer and is passed, in whole or in part, via line 32 to tower 10. Sulfur dioxide is likewise recycled via line 30 to tower 10.

The process of the present invention may be subjected to many variations without departing from its spirit. Thus, instead of separately heat treating the oil prior to addition of solvent, it may be desirable, under certain circumstances, to thermally treat the oil-solvent mixture preferably after saturation with the coagulating gas. In still another modification, total crude, from which fixed gases have been stripped, may be fed to the heat soaking vessel 8 and then to the countercurrent contacting tower 10. Naphtha recycle is fed to the top of the tower equivalent to about 0.1 to 10 volumes on feed. The naphtha cut may be of various boiling ranges or the total fraction boiling up to about 400° F. The naphtha-deashed oil solution is taken overhead from the contacting tower to a distillation tower where the naphtha recycle stream is cut out and excess naphtha from the crude taken off as make naphtha. The SO₂-residue stream is taken from the bottom of the tower and decomposed as described hitherto. The SO₂-HCl fraction is taken overhead from the still and compressed for recycling. Operating in this manner integrates the distillation step after the solvent precipitation process, and produces both the precipitant for the demetallizing process as well as any other cut desired in the crude distillation step.

The process of the present invention yields an oil with very low metal content from a highly contaminated stream, as shown below.

The following experiments were carried out with Bachaquero crude topped at 400° F. in order to illustrate the effects of the variables involved. The Bachaquero topped crude is representative of the Venezuelan heavy lake crudes containing large amounts of vanadium and nickel components. The sample used had a gravity of 14.1° API, a Furol viscosity of 187 SSF at 122° F., and contained 450 p.p.m. vanadium, 50 p.p.m. nickel, 2.3 wt. percent sulfur and 0.38 wt. percent nitrogen with a Conradson carbon content of 11.3 wt. percent.

The data below show the superior selectivity obtained by treatment with heavier hydrocarbons as compared with conventional deasphalting using propane. The propane deasphalting results are taken from correlations to show data at both the same yield and at the same degree of metals removal. Results were obtained with the Bachaquero topped crude which had not been subjected to heat treatment.

Treatment	Recovered Oil	
	Vol. Percent Yield	P.p.m. Ni+V
3 Vol. Pentane/1 Vol. Feed	94.4	137
Propane Deasphalting:		
Same Yield	94.4	340
Same Metals Removal	79.4	137
3 Vol. Hexane/1 Vol. Feed	97.0	122

It is thus seen that the heavier paraffin, n-pentane, gives a much higher yield of oil for the same degree of metals removal or a much higher metals removal for the same oil yield. This trend is also shown for the use of n-hexane as compared with n-pentane although the degree of difference is not so great.

The following data show that more severe heat-treatment of the feed improves metals removal, at least up to the point of removing all but a few p.p.m. of metals

content. These treatments were carried out with Bachaquero topped crude after the indicated heat treatment by adding 3 volumes of n-pentane, saturating the mixture with anhydrous HCl gas and adding about one-half volume of liquid sulfur dioxide. Under these conditions the precipitate immediately separated as a semi-fluid sludge at the bottom of the reaction vessel.

Heat Treatment	Recovered Oil	
	Vol. Percent	P.p.m. Ni+V
Feed.....	100	500
None.....	89	39
4 Hours at 700° F.....	86	12
4 Hours at 725° F.....	85	5
4 Hours at 750° F.....	89	4
1 Hour at 750° F.....	87	22

Heat treatment for shorter periods of time at higher temperatures does not appear as good for metals removal as longer heating at low temperatures.

Data obtained with Bachaquero topped crude heat soaked for 4 hours at 725° F. show the effect of the various treatment steps described above.

Treatment	Recovered Oil	
	Vol. Percent	P.p.m. Ni+V
3 Vol. n-C ₆	87.3	27
3 Vol. n-C ₆ +HCl Gas.....	86.7	11
3 Vol. n-C ₆ +0.5 Vol. SO ₂	89.2	13
3 Vol. n-C ₆ +HCl+SO ₂	85.0	5
3 Vol. C ₆ /C ₇ Naphtha+HCl+SO ₂	85.8	11
1 Vol. C ₆ /C ₇ Naphtha+HCl+SO ₂	85.5	16

The combination of both treatment with HCl gas and sludging with liquid sulfur dioxide gives much better metals removal than either treatment alone. The above data also show that a C₆/C₇ light naphtha boiling from about 110° to 180° F. is a satisfactory diluent. This material gives somewhat poorer metals removal than the light n-paraffins because of the enhanced solvent power of the benzene contained therein. The ready availability of such naphtha fractions, however, offsets this slight disadvantage. Data obtained with the naphtha also show that the degree of metals removal can be controlled by the amount of diluent added, larger amounts removing more metals, although equivolume naphtha is still very effective.

The following data show that in addition to metals removal there are other quality improvements for the oil product such as increased gravity, decreased Conradson carbon, decreased viscosity and decreased nitrogen content. All of these improvements increase the value of the feed for catalytic cracking and other general uses.

Severe solvent precipitation treatment gives product approaching catalytic cracking feed quality

The following data show that the 700° F. + bottoms of Bachaquero crude representing the bottom 76% of the topped crude is similarly improved by this treatment. Also data are included which show that a domestic crude, 400° F. Hawkins topped crude, of much lower metals content is improved by this treatment. These feeds were heat soaked for 4 hours at 700° F. before being treated with 3 volumes of n-pentane, saturated with HCl and sludged with 0.5 volume of liquid sulfur dioxide.

In an additional experiment a mixture of Bachaquero topped crude and three volumes of n-pentane saturated with HCl gas was heat-soaked for 4 hours at 700° F. 25 The product oil was recovered in 89 vol. percent yield on feed and had a nickel plus vanadium content of 20 p.p.m. These results are similar to those expected for treatment of the feed heat-soaked under the same conditions with 3 volumes of n-pentane and saturated with 30 HCl gas.

What is claimed is:

1. An improved process for upgrading a metallic contaminated petroleum fraction including constituents boiling above about 950° F. which comprises subjecting said fraction to an initial thermal treatment at a temperature between about 600° to 900° F. for a period of 0.1 to 5 hours, thereafter contacting said fraction in a precipitation zone with 0.1 to 10 volumes of a light hydrocarbon per volume of oil, an acid gas and about 0.1 to 3.0 35 volumes of liquid SO₂ per volume of oil, thereby precipitating and coagulating metallic contaminants and separating a heavy oil substantially free from the precipitated and coagulated metallic contaminants.

2. The process of claim 1 wherein said acid gas is 40 hydrogen chloride.

3. An improved process for upgrading a metal contaminated petroleum fraction containing constituents boiling above 950° F. which comprises heat-soaking said fraction at a temperature of from about 650° to 850° 45 F. for a period of about 0.1 to about 5 hours, in a heat soaking zone, thereafter mixing said heat soaked oil with 0.1 to 10 volumes of a hydrocarbon having from 5 to 10 carbon atoms in a precipitation zone, saturating said mixture with gaseous HCl, maintaining precipitation 50 conditions of 30 to 300° F. and 25 to 500 p.s.i.g. in said zone, sludging said mixture with 0.1 to 3 volumes per volume oil of liquid anhydrous SO₂, and recovering a heavy oil greatly depleted in metallic impurities.

4. The process of claim 3 wherein said oil is heat 55 soaked for about 4 hours at about 750° F.

5. The process of claim 3 wherein topped crude is passed sequentially to said heat soaking zone and said precipitation zone, a naphtha fraction passed to said zone, a mixture of naphtha and deashed oil withdrawn 60 from the upper portion of said zone and passed to a distillation zone.

6. The process of claim 3 wherein a sludge formed in said process is decomposed into solid carbonaceous material and gaseous SO₂ and hydrocarbons by directly 65 contacting said sludge in a coking zone with a bed of fluidized solid carbonaceous material heated to a temperature in the range of about 100° F. to about 1000° F. and maintaining said bed in a fluidized state by recycling a portion of the gaseous SO₂ and hydrocarbon 70 liberated in said coking zone.

7. The process of claim 6 wherein said heavy oil is recovered by passing a liquid mixture separated from the sludge to a flashing zone, withdrawing from said flashing zone a gaseous mixture of said hydrocarbon, HCl and SO₂, combining said gaseous mixture with a portion of the gases withdrawn from the coking zone, passing said gases to a settling zone maintained at conditions of decreased temperature and increased pressure to condense the gaseous SO₂ and hydrocarbon while maintaining the HCl in a gaseous state and separately withdrawing from said settling zone a liquid SO₂ stream, a liquid hydrocarbon solvent stream and a gaseous HCl

stream and recycling said streams to the precipitation zone.
